UNITED STATES PATENT OFFICE.

ISRAEL GREENBERG, OF BALTIMORE, MARYLAND.

ROOFING-TILE.

1,391,891.

Specification of Letters Patent. Patented Sept. 27, 1921.

Application filed December 14, 1920. Serial No. 430,593.

To all whom it may concern:

Be it known that I, ISRAEL GREENBERG, a citizen of the United States, residing at Baltimore, in the State of Maryland, have 5 invented certain new and useful Improvements in Roofing-Tiles, of which the following is a specification.

This invention relates to improvements in roofing tiles, and has for its object to provide 10 a tile that is especially adapted for roofing and similar purposes, and which is simple and durable in construction and so formed that when placed in position the overlapping ends will interlock and form 15 a tight joint as well as to prevent the ends of the tiles from being raised by the wind or otherwise. A further object of my invention is to prevent breakage of the tile in shipment or in handling same.

20 The invention consists of the novel construction and arrangement of the parts hereinafter more fully set forth in the following specification and pointed out in detail in the appended claim.

25 In the accompanying drawing,

Figure 1 is a top plan view of my improved tile.

Fig. 2 is an inverted plan view of same.

Fig. 3 is a section on the line 4—4 of 30 Fig. 1.

Fig. 4 is an end view of Fig. 2.

Referring to the accompanying drawing, forming part of this specification, and in which like reference numerals designate like 35 parts throughout the several views thereof, 1 designates the body of the tile which is provided with two grooves 2 in its upper surface and a central groove 3 in its under surface. The upper surface of the tile is 40 also provided with grooves 4 at one side to receive the projection 5 on the underside of the overlapping edge of the adjoining tile.

One end of the tile is provided with an integral piece 6 extending from one side of the tile to a point where the adjoining tile overlaps thus forming a continuous piece across the edge of the tiles when laid together thereby preventing the rain or water from being blown up under the tile when laid in position. On the underside of the tile are 45 two lugs 7 which fit under the strips of the roof (not shown) and two lugs 9 which fit into the grooves 2 just back of the cross piece 6 of the tile below. The under surface of the tile is also provided with two parallel 50 projections 10 near the center thereof and on opposite sides of the groove 3. A wire 11 is embedded in the projections 10 and extends across the groove 3 and rests upon the upper surface of the webs 12 which are 55 integral with the tile and have their lower surfaces flushed with the lower surface of said tile. The said wire 11 strengthens the tile in the middle where the greatest strain 60 generally occurs and will reduce the breakage of same either lengthwise or crosswise.

Having thus described my invention what I claim is:—

A roofing tile having its sides adapted to overlap and two grooves in its upper surface and a central groove in its lower surface thereof, two lugs on the lower surface of the tile adapted to fit in the grooves on the upper surface of the adjoining tile, two webs extending across the central groove 3 70 and having their lower surfaces flushed with a lower surface of the tile, two integral parallel projections on the lower surface of the tile on opposite sides of said central groove, and a wire embedded in said projections and extending across and resting 75 against the lower surface of said webs.

In testimony whereof I affix my signature.
ISRAEL GREENBERG.
